**COMBINED FOOT REST AND DIMMER
SWITCH PEDAL**

**Nathan K. Morris, 4th and Railroad Aves.,
Neptune City, N.J.**

Filed May 28, 1962, Ser. No. 70,327

Term of patent 7 years

(Cl. D14—6)

FIGURE 1 is a side elevational view of a combined foot rest and dimmer switch pedal showing my new design;

FIGURE 2 is a top plan view thereof;

FIGURE 3 is an elevational view thereof taken from the left of FIGURE 1;

FIGURE 4 is a bottom plan view thereof, and

FIGURE 5 is a sectional view, as seen on line 5—5 of FIGURE 1, looking in the direction of the arrows.

I claim:

The ornamental design for a combined foot rest and dimmer switch pedal, as shown.
